UNITED STATES PATENT OFFICE

HERMAN C. REICHHARDT, OF EVANSTON, ILLINOIS, ASSIGNOR, BY DIRECT AND MESNE ASSIGNMENTS, TO STAR-BRITE CORPORATION, OF CHICAGO, ILLINOIS, A CORPORATION OF ILLINOIS

DESIGN FOR A GLASS LENS FOR LIGHT REFLECTOR SIGNAL

Application filed December 31, 1931. Serial No. 42,327. Term of patent 14 years.

To all whom it may concern:

Be it known that I, HERMAN C. REICHHARDT, a citizen of the United States, residing in the city of Evanston, in the county of Cook and State of Illinois, have invented a new, original, and ornamental Design for a Glass Lens for Light Reflector Signal, of which the following is the specification, reference being had to the accompanying drawing, forming part thereof.

Figure 1 is a front elevation of the glass lens.

Figure 2 is a rear elevation of the same. Figure 3 is a side or edge view of the glass lens.

Figure 4 is a section taken on the line 4—4 of Figure 2.

I claim:

The ornamental design for a glass lens for light reflector signal, as shown.

HERMAN C. REICHHARDT.
